UNITED STATES PATENT OFFICE.

CARL WANINGER, OF DUSSELDORF, GERMANY, ASSIGNOR TO THE FIRM OF
RHEINISCHE METALL-WAAREN-UND MASCHINENFABRIK, OF DUSSELDORF,
DERENDORF, GERMANY.

PIVOT GUN, PARTICULARLY ADAPTED FOR SUBMARINES.

Application filed June 28, 1921. Serial No. 481,060.

To all whom it may concern:

Be it known that I, CARL WANINGER, engineer, a citizen of Germany, residing at Dusseldorf, Germany, have invented certain new and useful Improvements in Pivot Guns, Particularly Adapted for Submarines, for which I have filed application in Germany, June 4, 1918, and of which the following is a specification.

10 The invention relates to an improvement for a gun to be used on submarine boats, which is of a construction as simple as possible in that part at least which is awash while the boat is submerged. Here 15 such guns are thought of, which are adapted to be pointed from inside of the submarine, in order to permit of the pointing being done without hindrance from the heavy seas, and in order to have the gun ready 20 for firing immediately after emerging, or that the boat may be ready at once to submerge after firing. It is no longer necessary for the crew to come out on deck, except for the loading man. Now it is most 25 important as regards the safety of the boat, that the latter is provided in its outer shell with as few perforations as possible, since these require special tightening means again.

This is attained to a large extent by the 30 present invention, in that only one single packing is required for movable parts, namely that which is to tighten up the pivot pin of the gun. At the same time said pivot pin will serve as a shaft for 35 transmission of the movement of the two pointing machines disposed in the hold of the boat, that is to say, of the machines for vertical and horizontal pointing.

The construction shows the further advantage of small resistance to the water when submerged, and besides the profile of the boat is not essentially enlarged by the 40 guns.

The pointing of such guns may be effected 45 in the following manner:

Aided by a periscope, projecting pressure-tightly from the boat (especially from the conning tower) the goal is made out. The movement of the prisms of the periscope 50 is transmitted by manual means or by machinery to hands or pointers arranged inside the boat near the gun in such a manner, that the individual movement of the boat

is added to or deducted from the angles of elevation. The marks-men now move the 55 gun by means of the pointing machines manipulated either by hand or machinery, so that the hands or pointers driven by the gun will continuously tally with those pointers adjusted from the conning tower. 60 Such devices have already become known in pointers of back-sights.

In the literature relating to gunnery furthermore devices have become known, which will admit of the guns to be pointed directly 65 from a point of sight in any desired distance, that is to say by dispensing with the intermediary, the marks-men above referred to.

In the drawing one modification according to the invention is illustrated, in which—

Fig. 1 is an elevation showing a longitudinal section through the boat and the pivot arrangements,

Fig. 2 is a horizontal section through the 75 hydraulic and compressed air cylinders on the line 3—y of Figure 1.

The barrel and cradle are shown in full lines in side elevation at an elevation of 0°, and in dotted lines at an elevation of 80 45°.

The cradle *a* rests with its trunnions *b* in the cradle support *c*, whose hollow pivot member *d* carrying a piston rests in the pedestal *f*, which is constructed as a hydraulic cylinder, being provided at the top with a packing-box *g* and at the bottom with a packing-box *h*. The pedestal is fastened to the pressure-safe body of the boat. The hollow journal *d* is provided at 90 its lower end with a packing-box *k*, through which a plunger *l* is extending into the pivot member *d* adapted to be used as a compressed air cylinder. Said plunger is guided in the journal *d* by means of a groove 95 and key *w*, so that it is free to move longitudinally therein; its turning however will cause the horizontal pointing movement of the gun. For this purpose, the plunger *l* which rests by means of a ball-bearing *m* 100 upon the bottom *n* of the boat, carries a toothed wheel *o*, through which the horizontal pointing motion is imparted by the machine for horizontal pointing, not shown.

The head of the pedestal *f* carries a ring 105 *p* moving on balls, said ring being provided

with two journals *q*. Guiding rods *r* connect these journals with other journals disposed at both sides of the cradle.

If the cradle support *c* is raised or lowered by introducing hydraulic pressure through the openings *u* or *v* on to the upper or lower face of the plunger *e*, the barrel of the gun will change its angle of elevation accordingly. In order to avoid lifting 10 of total weight of the barrel, cradle and cradle support, the hollow pivot member *d* is filled with compressed air, and in conjunction with the plunger *l* said pivot member will constitute an equalizer of 15 compressed air. The upper part of the compressed air cylinder is communicating with its lower part through borings *x*.

Besides the aspects pointed out in the premises, the gun constructed according to 20 the present invention offers the following advantages.

At a lesser elevation the height of firing is small and consequently the recoiling power absorbed by the shell of the boat will 25 be small too. At an increasing elevation the height of firing will increase but the horizontal component of the recoiling force become smaller. The small elevation of the barrel when firing horizontally affords easy 30 loading of the gun. Into this position the gun is preferably brought when the boat is to run submerged, so that the resistance of the water will be considerably less than with a gun of constant firing height.

35 Though hydraulic motion may be given the preference in the present instance, it would not mean departing from the subject matter of the invention, by substituting electrical motion, or to provide any other kind 40 of motive power for raising or lowering the support of the cradle.

It is obvious, that the invention may be advantageously used with other guns than with those for submarines.

45 I claim:

1. In a pivot gun particularly adapted for submarines, the combination with the body of a vessel, of a pivot member supported thereon and constructed to serve as a compressed air equalizer, a gun carried by the pivot member and means for raising and lowering the pivot member from within the vessel for adjusting the position of the gun.

50 2. In a pivot gun particularly adapted for submarines, the combination with the body of a vessel, of a pivot member sup-

ported thereon, a gun carried by the pivot member, means for raising and lowering the pivot member from within the vessel for adjusting the position of the gun and 60 means operable upon the raising and lowering of the pivot member for changing the angle of the gun said last means including a link pivoted at one end to the gun and at its opposite end to an axis diametrically 65 transverse of the pivot member for swinging in a plane parallel to the axis of said pivot member.

3. In a pivot gun, the combination with the body of a vessel, a pedestal supported 70 thereon, a pivot member slidable in the pedestal, a gun carried by the pivot member, means for raising and lowering the pivot member and rods pivotally connected at its opposite ends to the gun and pedestal for 75 causing the angle of the gun to be changed upon the raising and lowering of the pivot member.

4. In a pivot gun, a pedestal formed with an axially arranged cylinder, a hollow pivot member slidable in the pedestal and provided with a piston operating in the cylinder, a gun on the pivot member, and a plunger keyed in the hollow pivot member 80 for relative sliding movement.

5. In a pivot gun, the combination with the body of a vessel, of a pedestal mounted thereon, a pivot member slidably mounted on the pedestal, a gun carried by the pivot member, rods swiveled to the pedestal and 85 connected to the gun, and means for rotating and elevating the pivot member from within the inside of the vessel for the purpose of 90 adjusting the elevation of the gun, said pivot member being hollow and constructed to 95 serve as a compressed air equalizer.

6. In a pivot gun the combination with the body of a vessel, a hollow pivot member supported thereon, a gun carried by the pivot member, a rotatable plunger extending into the pivot member and keyed thereto, said plunger when rotated causing the horizontal 100 position of the gun to be changed, and means for raising and lowering the pivot member, said pivot member being adapted to serve 105 as a compressed air equalizer.

In testimony whereof I have affixed my signature in presence of two witnesses.

CARL WANINGER.
